UNITED STATES PATENT OFFICE.

JAMES M. ACHESON, OF PORTLAND, OREGON.

DISPLAY-CABINET.

No. 877,751.

Specification of Letters Patent.

Patented Jan. 28, 1908.

Application filed July 8, 1907. Serial No. 382,669.

To all whom it may concern:

Be it known that I, JAMES M. ACHESON, residing at Portland, in the county of Multnomah and State of Oregon, have invented 5 certain new and useful Improvements in Display-Cabinets, of which the following is a specification.

My invention relates to that type of cabinets used in stores for displaying garments, particularly women's and men's clothing and 10 it has for its object to provide a cabinet of this character of a very simple and economical construction adapted for sitting on the floor whereby the garments may be readily 15 displayed or taken in and out of the cabinet.

My invention comprehends also the peculiar correlation of parts hereinafter fully described, specifically pointed out in the appended claims and illustrated in the accompanying drawings, in which:

Figure 1 is a perspective view of a display cabinet embodying my invention, all of the doors being closed. Fig. 2, is a similar view, several of the doors being opened and forming 25 the mirrors for surrounding the customer. Fig. 3, is a vertical, cross section of the cabinet. Fig. 4, is a horizontal section taken on the line 4—4 of Fig. 3.

In the practical construction my improved 30 cabinet is of hexagonal shape in cross section, although it may be made up of a less or a greater number of sides.

The base or bottom portion which may be made of wood or light sheet metal, is suitably 35 ornamented or paneled as shown and from the corners of the sides that form the base rise the corner frames *a* that extend upwardly and support the solid top member *b* in any approved manner. Sustained from the top 40 of the casing and centrally thereof is a hanger post *c* on the lower end of which is rotatably mounted on a circular rack which consists of the annular rim *d*, the radial arms *e* that join the said rim with a tubular sleeve *f*, 45 that is mounted on lower end of the post *c*, said sleeve having a long bearing and has its lower end braced to the rim *d* by the upwardly diverging brace rods *g*—*g*, the said rotatable rack being held on the post by the 50 collar and nut devices *h* on the lower end of the said post, as shown.

Instead of mounting the circular rack on a hanger suspended from the top of the cabinet, it is manifest the said rack may be 55 mounted on an upright stand, but I prefer to support the said rack in the hanger since it is

thereby maintained in a fixed central position relatively to the cabinet walls for the reason presently explained.

The sides of the cabinet are alternately 60 stationary and movable ones, the movable ones being in the nature of hinged doors *i*, each of which has a mirror panel *i'*, on the outside and a mirror panel *i''* on the inside whereby when the doors are opened they will 65 form mirrors to close around the customer and thus prevent the necessity of going over to the wall mirror.

In using the circular rack, it is customary 70 to fill the same with coats and other garments individually suspended on hangers that are hung upon the circular rack, and in assembling the goods it is often desirable to arrange the same styles in different sizes or different priced garments, in lots.

To provide for holding the circular rack 75 stationary after a garment has been taken off to be tried on by the customer and the door is open, so that it is easy to return the garment to the right place, if necessary, or to 80 take out another garment of the same lot, I form the peripheral face of the rack rim surface with radial undulations or bevel projections *d'* preferably in the nature of a resilient band bent to the proper shape and secured to the said annular rim *d*, as shown.

On each door at the upper edge thereof is a flexible finger *k* having a rounded edge adapted when the door is open to engage the resilient rim member and exert sufficient pressure on the rack to hold it from too easily turning, but not sufficient to prevent it being turned by force when desired. The sides of 90 the cabinet other than the door sides are transparent so as to display the contents of 95 the cabinet.

From the foregoing taken in connection 100 with the drawings, the complete structure and the advantages of my invention will be readily apparent.

It will be noticed that while the cabinet provides for holding the desired garments in position for display, that as soon as the door or doors are opened the customer has the desired mirror surface surrounding him necessary to enable him to note the fit of the garment being tried on, while at the same time in opening, the rack is automatically held from a free rotation and held with that particular lot of goods from which the selection 105 is being made at the open door, it being manifest that the rack hold-back is not of suffi-

cient force to prevent the rack being further rotated without shutting the door or releasing the engagement of the check member from the rack rim since said members are sufficiently flexible to permit of a further rotation of the rack under pressure.

Having thus described my invention, what I claim and desire to secure by Letters Patent, is:

- 10 1. In combination with a cabinet having one or more hinged doors, and a clothes rack rotatably mounted in the cabinet, means for engaging with the rack to hold it from freely rotating, said means being automatically set in operation when any of the doors of the cabinet are swung open.
- 15 2. In combination with a cabinet having one or more hinged doors, a circular rack rotatably mounted in the cabinet, said rack

having its peripheral face provided with undulations, and a flexible member on each of the doors adapted to engage with the undulated surface of the rack when any of the doors are opened.

- 20 3. The combination with a cabinet having one or more outwardly swung doors, a circular rack suspended from the top of the cabinet and rotatable on its support, said rack including an annular rim and a resilient member secured thereto having radial beveled projections and a flexible member on each door, each having a rounded end for engaging the beveled projections on the rack rim for the purposes specified.

JAMES M. ACHESON.
